UNITED STATES PATENT OFFICE

151,298

DESIGN FOR A HELICOPTER

Frank L. Sutton, Buffalo, N. Y., assignor to Bell
Aircraft Corporation, Wheatfield, N. Y.

Application August 22, 1947, Serial No. 140,993

Term of patent 14 years

(Cl. D71—1)

To all whom it may concern:

Be it known that I, Frank L. Sutton, a citizen of the United States, residing at 254 Manhattan Avenue, in the city of Buffalo, county of Erie, and State of New York, have invented a new, original, and ornamental Design for Helicopter, of which the following is a specification, reference being had to the accompanying drawing, forming part thereof.

Fig. 1 is a top plan of a helicopter, showing my novel design;

Fig. 2 is a side elevational view thereof; and

Fig. 3 is a front end elevational view thereof.

The novel features of the invention reside in the portions shown in solid lines.

I claim:

The ornamental design for a helicopter, as shown and described.

FRANK L. SUTTON.
